UNITED STATES PATENT OFFICE

FRANK NAGEL, OF FREMONT, OHIO; MARY NAGEL, EXECUTRIX OF SAID FRANK NAGEL, DECEASED; ASSIGNEE TO THE CRESCENT MANUFACTURING COMPANY, OF FREMONT, OHIO, A CORPORATION OF OHIO

DESIGN FOR A RAZOR BLADE

Application filed February 7, 1930. Serial No. 34,450. Term of patent 14 years.

To all whom it may concern:

Be it known that I, FRANK NAGEL, a citizen of the United States of America, and resident of the city of Fremont, county of Sandusky, and State of Ohio, have invented a new, original, and ornamental Design for a Razor Blade, of which the following is a specification, reference being had to the accompanying drawings, forming part thereof.

I claim:

The ornamental design for a razor blade as shown.

FRANK NAGEL.
